INVENTOR.

Osceola C. Thompson
BY Edward D. Munro Jr.

ATTORNEY.

UNITED STATES PATENT OFFICE.

OSCEOLA C. THOMPSON, OF ROCKAWAY, NEW JERSEY, ASSIGNOR TO WIREBOUNDS PATENTS COMPANY, A CORPORATION OF MAINE.

BOX AND METHOD OF MAKING THE SAME.

Original application filed July 25, 1918, Serial No. 246,722. Divided and this application filed February 25, 1922. Serial No. 539,257.

To all whom it may concern:

Be it known that I, OSCEOLA C. THOMPSON, a citizen of the United States, and a resident of Rockaway, in the county of Morris, in the State of New Jersey, have invented new and useful Improvements in Boxes and Methods of Making the Same, of which the following is a specification.

This invention relates to boxes and to a method of manufacturing the same, and particularly to wire-bound boxes and fastening means therefor.

Among other objects, the invention is intended to provide an improved wire-bound box of general utility as a shipping container and to provide such a box with improved fastening means for connecting adjacent box parts one with another.

This application is a division of my co-pending application Serial No. 246,772, filed July 25, 1918, which is directed to a machine for use in making the box described and claimed herein.

The invention will be best understood by reference to one illustrative embodiment thereof shown in the accompanying drawings, in which:

Fig. 1 is a top plan view of a sectional wire-bound box blank embodying the invention;

Fig. 2 is a perspective view of a box formed from the blank shown in Fig. 1, with the lid or cover partially raised.

Fig. 3 is a perspective view of a box formed from the blank shown in Fig. 1, after the lid or cover is lowered into closed position, and showing also the fastening means for holding the lid or cover in closed position;

Figs. 4 and 5 are enlarged front elevations of a portion of the box shown in Fig. 3, illustrating the manner of cooperation of the fastening means; and

Figs. 6, 7 and 8 are enlarged detail views of the fastening means.

In the manufacture of sectional wire-bound boxes, it has been proposed to connect adjacent sections by forming loops or bights on the ends of the wires secured to such sections and hooking one loop or bight through the other. Heretofore, the male member of the connection was formed smaller than the opening of the female member in order to readily pass therethrough and consequently

the holding power of the connection between the two members was dependent upon the hooking engagement alone and when the male member became straightened under stresses and strains the holding power of the connection ceased. In applicant's invention, the members of the connecting means are so formed that the male member will be held in locking engagement with the female member in the absence of any hooking engagement between the male member and the female member, thus either eliminating the hooking operation, or increasing the holding power of the connection in cases in which the hooking operation is utilized.

The illustrative box shown in Fig. 3 is formed by folding the box blank shown in Fig. 1 about end sections and joining the mating wire ends which are provided with applicant's improved fastening or connecting means.

The illustrative box blank comprises four separate sections of side material 1 and cleats 2 connected together in foldable relationship by binding wires 3 secured thereto by staples 4, which wires are supplied at one end with a bight 5 and at the other end with a bight 6 adapted to interengage in the manner hereinafter described when the blank is folded into box form. The end sections 7, about which the blank is folded, are preferably fastened to the inner faces of cleats of the blank sections by means of staples or other fastening means.

The interengageable bights 5 and 6 which may be identical in size and form are supplied on the wire ends in definite relation to the box part edge by bending the wire back upon itself and intertwisting the end of the wire and the main body of the wire as shown at 8 in Fig. 6. A suitable machine for performing this operation is shown in my copending application Serial No. 246,772 above referred to. The bights 5 and 6, as best shown in Figs. 6, 7 and 8, are so formed that the opening is slightly longer than the width of the bight (outside measurement) and only slightly wider than the cross section of the twisted portion 8 of the wires so that bight 6 on the box side in Fig. 2 when properly presented will readily pass through the opening in bight 5 on the lid or cover when the same is lowered to close the box as shown.

in Figs. 4 and 7. After the bight 6 has been passed through the opening in bight 5, as shown in Fig. 4, it may be given a quarter turn, thus locking bight 6 against displacement as shown in Figs. 5 and 8. To further strengthen the closure of the box, the bight 6 may be drawn taut through the bight 5 and then bent downward against the side of the box as shown at the left in Fig. 3. This hooking operation may be performed with a nail or any suitable prying implement. The bights are preferably so formed and positioned that in hooking the bight 6 through the bight 5 the bend or hook will occur at the twisted portion 8 which is considerably stronger and more resistent to strains than a pair of wire strands which have not been so intertwined.

Among other advantages, applicant's invention provides an efficient means for quickly and easily connecting and disconnecting adjacent box sections; it provides an efficient connection without any hooking engagement; and in cases in which a particularly strong connection is required it supplies additional holding power to the holding power exerted by the hooking engagement because, in addition to the holding power exerted by the hooked portion 8 of the male member of the fastening means when it is hooked down against the side of the box, the male member is capable of maintaining its engagement with the female member after the hook has been straightened out under stresses and strains to which the box may be subjected. The fact that applicant's fastening means will close the box without any bending or hooking operation is particularly advantageous in cases in which repeated opening and closing of the box is necessary because repeated bending back and forth of the male member of the fastening weakens said member and, in time, causes it to break. Thus the elimination of a number of such bending operations prolongs the life of the box.

It will be seen that I have produced a sectional wire-bound box having its binding wires supplied with interengageable fastening means to detachably connect adjacent sections; that said interengageable fastening means on adjacent sections may be identical in size and form and yet are capable of being passed one through another, and that by reason of the form of said fastening means they will be locked against disengagement by simply passing one through the other and giving the former a quarter turn.

The preferred method of manufacture is characterized by assembling the several sections of side material and cleats in cooperative foldable relationship, applying binding wire thereto and supplying its ends with the interengageable bights hereinbefore de-

scribed in proper relation to the box part edges, folding the box blank about end sections and interengaging the bights on adjacent sections in the manner described.

Obviously, the invention is not limited to the specific embodiment herein shown for illustration but may be variously embodied without departing from the invention and, while I have illustrated a box in which only two of the adjacent sections are connected by the interengageable fastening means, it will be understood that any or all adjacent sections may be so connected and that the fastening means shown may be used to advantage in other forms of package and in other ways.

Having described my invention, what I claim is:

1. In combination, a plurality of wired box sections and means to connect the same comprising a bight having an opening longer than the width of the bight carried by one of said sections, and a similar bight of approximately the same size and shape carried by another section for interengagement with said first mentioned bight. 85

2. In combination, a plurality of wired box sections and means to detachably connect the same comprising a bight having an opening longer than the width of the bight carried by one of said sections, and a similar bight of approximately the same size and shape carried by another section for detachable engagement with said first mentioned bight. 95

3. In combination, a plurality of wired box sections and means to connect the same comprising a bight having an opening longer but narrower than the width of the bight carried by one of said sections, and a similar bight of approximately the same size and shape carried by another section for interengagement with said first mentioned bight. 105

4. In combination, a plurality of wired box sections and means to connect the same comprising a bight having an opening longer but narrower than the width of the bight formed on the wire end of one of said sections, and a similar bight of approximately the same size formed on the wire end of another section, whereby one bight may be passed through the opening in the other and when turned a portion of a revolution be held in locking engagement thereby. 110

5. A wire-bound box having a binding of wire secured thereto and joined thereabout, each end of said wire being provided with a bight of approximately the same size and shape having an opening longer than the width of the bight whereby one bight may be passed through the other. 115

6. A wire-bound box having a binding of wire secured thereto and joined thereabout, each end of said wire being pro- 125

vided with a bight of approximately the same size having an opening longer but narrower than the width of the bight whereby one bight may be passed through the 5 opening in the other and when turned a portion of a revolution be held thereby in locking engagement.

7. The method of connecting wired box sections which is characterized by supplying the wires of said sections with 10 cooperating bights of approximately the same size having an opening longer but narrower than the width of the bight; by inserting one bight through another; and by giving 15 the first mentioned bight approximately a quarter turn.

8. The method of connecting wired box sections which is characterized by supplying the wires of said sections with 20 cooperating bights of approximately the same size having an opening longer but narrower than the width of the bight; inserting one bight through the other; giving the first bight approximately a quarter turn; and 25 bending the first bight back upon itself.

9. The method of connecting wired box sections which is characterized by supplying the wires of said sections with 30 cooperating bights of approximately the same size having an opening longer but narrower than the width of the bight and having a throat of twisted strands; inserting one bight through the other; giving the first bight approximately a quarter turn; and 35 bending the throat of the first bight to form

a hooking engagement with the other bight.

10. The method of forming a sectional wire-bound box which is characterized by assembling a plurality of sections of box material in cooperative foldable relationship; applying binding wire thereto; supplying ends of the binding wire with 40 cooperative bights of approximately the same size and having an opening longer but narrower than the width of a bight; folding the sections into box form; inserting one bight through the opening of another bight and giving the first bight approximately a quarter turn to effect a locking engagement 45 with the other bight.

11. The method of forming a sectional wire-bound box which is characterized by assembling a plurality of sections of box material in cooperative foldable relationship; applying binding wire thereto; supplying ends of the binding wire with 50 cooperative bights of approximately the same size and having an opening longer but narrower than the width of a bight; folding the sections into box form; inserting one 55 bight through the opening of another bight; giving the first bight approximately a quarter turn to effect a locking engagement with the other bight; and bending the first bight 60 back upon itself to effect a hooking engagement with the other bight.

In testimony whereof, I have signed my name to this specification.

OSCEOLA C. THOMPSON.
